WIRELESS SIGNALING SYSTEM

Application filed December 21, 1926, Serial No. 156,095, and in Germany December 24, 1925.

Our invention has reference broadly to wireless signaling systems and is more particularly intended to provide means for reducing undesired oscillations such as higher harmonics or side frequencies and other interfering frequencies in wireless signaling circuits.

Our invention finds particular application in such cases where disturbing frequencies are present which are more or less symmetrical to the operating or signaling frequency and which are known in the art as side-frequencies. Such frequencies occur especially in systems comprising a high-frequency generator of a fundamental frequency in combination with one or more iron-cored high-frequency transformers. It has become very well known in the art of wireless signaling to eliminate undesired oscillations by the employment of intermediary circuits, rejector and acceptor circuits, filters and the like.

According to our invention we also make use of the working of rejector and acceptor circuits and our invention presents a novel combination thereof in providing several paths in connection with a signaling circuit, each path consisting of an acceptor circuit tuned to one of the undesired frequencies and therefore presenting zero impedance for this particular frequency and whereby the tuning of the several acceptor circuits is so adjusted that in their resultant action with respect to the operating (signaling) frequency they form a rejector circuit for the latter and thus prevent the signaling frequency from entering the by-pass and force it back or reject it into circuit portions to be actively employed in the system for signaling purposes. The effective impedance of the by-pass is then increased in value for the particular signaling frequency, whereby the signaling frequency is confined to the signaling circuit and the by-pass is rendered opaque to the signaling frequency, while the undesired frequencies may pass freely thru the transparent acceptor circuits constituting the elements of the rejector circuit arrangement of our invention.

Our invention will be more clearly understood by the following detailed disclosure

and specific example in connection with iron-cored high-frequency transformer systems reference being taken to the accompanying drawings, in which Fig. 1 is a wiring diagram showing a portion of a signaling circuit with the circuit of our invention associated therewith, and of which Figure 2 is a wiring diagram of an iron-cored frequency transformer system with several circuits of our invention associated therewith, while Figures 3 to 4 inclusive are illustrative curves making clear the working principles underlying the high-frequency signaling system as represented by Fig. 2.

Referring more particularly to Figure 1 of the drawings the invention is shown applied to an antenna ground system indicated by reference characters 1 and 2. Coupling inductance 3 and tunable loading coil 4 are included into this circuit forming the usual tuned oscillatory system. Preceding this antenna circuit is an intermediary circuit composed by coupling inductances 5 and 6, capacity 7 and tuning inductance 8. A coupling inductance 9 imparts to the intermediary circuit high-frequency oscillating currents from a generating system of any kind well-known in the art and not indicated in the drawing for simplicity's sake. In the case the circuit relates to a receiving system the inductance 9 leads to a detector or amplification circuit. Accepter circuits composed by inductances 10 and 12 and capacities 11 and 13 respectively and being tuned each to one undesired frequency lying at either side of the signaling frequency and therefore presenting zero impedance for same serve as a by-pass to such frequencies. The one accepter circuit e. g. 10, 11 then presents a resultant capacitive reactance 14 for the signaling frequency and the other 12, 13 a resultant inductive reactance 15 for same or vice versa, which resultant reactances are indicated in the drawing by dotted lines. The values of this capacitive and inductive resulting reactances 14 and 15 respectively are dependent of the relation of the capacitive reactances 11 and 13 of the accepter circuits to their inductive reactances 10 and 12, respectively, as for the tuning of the acceptor

circuits there is only necessary a distinct product of their capacity and inductance (frequency f being equal as is well known to

$$5 \quad \frac{1}{2\pi\sqrt{LC}}$$

wherein L is the inductance and C the capacity of a tuned circuit), these relations may be so chosen and adjusted, that the resultant reactances 14 and 15 respectively in respect to the signaling frequency form in their combined action a rejector circuit for this latter forcing it thereby into the portions of the circuits system actively employed for signaling e. g. thru coupling coil 5 in the case of a transmitter or thru coupling coil 6 in the case of a receiver. Thus the signaling frequency is prevented from passing in part thru the by-pass circuit, and losses of the active signaling energy involved by such by-passing are eliminated.

Referring now more particularly to Figure 2 of the drawing, similar reference characters to that in Figure 1 refer to similar elements. 16 and 17 represent static frequency transformers with iron cores 18 and 19 and windings 20 and 21 respectively. The transformer 16 is energized by an alternating current source of a fundamental frequency e. g. a high-frequency generator 22, and the transformer 17 forming a second transformation step is energized by the first transformer 16, the two transformers thus being arranged in cascade connection which is generally employed when carrying out a very high-frequency transformation. The further elements forming part of the system are the tuning self-inductances 23 and 24 and the capacities 25 and 26 of the transformer output circuits respectively called also multiplication or impulse circuits as will be understood by the following detailed description of the working of the system.

The iron-core structure of the transformer is given so little iron, that it is already saturated by a very small portion of the amplitude value of the input (fundamental) alternating current. Hence, at the terminals of the transformer there occur only very sharp tension peaks periodically succeeding each other at exactly equal intervals (i. e. at a frequency of the alternations of the fundamental current), which tension peaks act upon the associated multiplication or impulse circuit (20, 23, 21, 25 and 21, 24, 9, 26) in a similar manner well-known with spark transmitters by impulse action and giving rise to free damped oscillation trains in the natural frequency of the impulse circuit. These oscillation trains, because of their rapid succession present a continuous oscillation wave such as represented by the Figure 3 of the drawings. The oscillations die out to a certain extent to be increased to their

original value periodically when a new tension peak occurs. By reducing the damping factor of the impulse circuit to the smallest value possibly by utilizing a small-capacity and a large inductance the dying out of the single wave trains may be minimized to such an extent that an almost sustained or undamped high-frequency current wave is obtained. However, especially when very high-frequencies are to be generated i. e. when very large transformation ratios are employed (e. g. the seventeenth of a fundamental frequency) no purely sinusoidal oscillations but of a shape more or less similar to that represented by Figure 3 will be obtained. Such a curve according to Fig. 3 equals a modulated high-frequency current and may therefore be resolved into the carrier frequency and a number of frequencies lying symmetrically at both sides of same and known as side-band frequencies. For instance an oscillation having sinusoidal amplitude-variation or in technical language being sinusoidally modulated as represented by a in Figure 4 may be resolved into oscillations of constant amplitudes consisting of the carrier frequency c and side-band frequencies b and d lying symmetrically at both sides of the carrier frequency. If the amplitude of the oscillations does not vary according to a pure sine law but according to an irregular periodical law such as e. g. is shown by Figure 3, this variation may be dissolved at its part according to Fourier's theorem into a plurality of pure sine variations the result being of the presence of not only one, as in case of Figure 4, but of a number of pairs of symmetrical side-frequencies. Thus in signaling systems employing frequency transformation apparatus of the character described, one or more pairs of side frequencies may occur which are radiated likewise the signaling frequency by a radiating system and may cause interference in the receiving apparatus. By employing circuit arrangements in accordance with our invention these disturbing side-frequencies may be prevented from being radiated and thus interference disturbances substantially eliminated. Referring once more to Figure 2, the self-inductance 27 and the capacity 28 on the one hand and the self-inductance 29 and the capacity on the other hand are so adjusted that the circuit 27, 28 is tuned to one of a pair of side-frequencies presenting zero impedance for same and equally circuit 29, 30 is tuned to the other side-frequency lying symmetrically with respect to the signaling frequency and presenting zero impedance for same. The result is that of only the ohmic resistance for these corresponding side-frequencies remain in both acceptor circuits 27, 28 and 29, 30 respectively. The whole circuit 27, 28, 29, 30 forms a rejector circuit for the signaling frequency, by ad-

justing a suitable relation of inductance 27 to capacity 28 and inductance 29 to capacity 30 respectively in the same manner as described with reference to Figure 1.

5 The circuit associated in accordance with our invention may also be arranged in a multiple way for the elimination of more pairs of disturbing frequencies or for increasing the effect to be obtained. According to Figure 2 an eliminating circuit arrangement is arranged also in the impulse circuit of the second frequency transformer, 31 and 33 being the inductances and 32 and 34 the capacities of its acceptor circuit elements respectively. Also the intermediary circuit placed between the multiplication circuit of the second transformer stage and the antenna system may contain a circuit arrangement according to our invention in conformity with the signaling system represented by Figure 1.

20 We may also provide three or more acceptor circuits by-passing three or more undesired frequencies and forming in their combined action a rejector circuit for the signaling frequency.

25 When dealing with frequency transforming systems as represented by Figure 2 it is necessary, according to a further object of our invention, to provide an eliminating circuit arrangement already in the first impulse circuit as the side-frequencies existing in this latter would be multiplied by the following transformation step and side-frequencies in the second impulse circuits would be so numerous and so close to the signaling frequency, that not even rejector circuits with the highest selectivity would be able to reduce them to a sufficient degree.

30 The principle of operation of our invention as pointed out may be employed with any sort of signaling circuits especially those where undesired frequencies may be combined into groups enabling the embodiment of a circuit arrangement according to our invention and while we have described our invention in certain specific embodiment, it will be understood that we intend no limitations other than are imposed by the scope of the appended claims.

35 Having thus described our invention, what we claim and desire to be secured by Letters Patent of the United States is:

40 1. In a wireless signaling system, an iron-cored frequency transformer having input and output circuits, means for applying a fundamental frequency to the input circuit of said transformer, means whereby a signaling current whose frequency is a multiple of said fundamental frequency flows in said output circuit, said last means being responsible also for a plurality of currents of undesired side frequencies produced besides said signaling frequency, a signaling circuit connected to said output circuit, a second

45 circuit comprising a plurality of acceptor circuits connected to said output circuit, one acceptor circuit being provided for each of objectionable side frequencies for by-passing these side frequencies from said signaling circuit, said acceptor circuits being so tuned that in their combined action they constitute a rejector circuit for the signaling frequency. 70

50 2. In a wireless signaling system, a plurality of iron-cored frequency transformers arranged in cascade connection, each having input and output circuits, means for applying a fundamental alternating current to the input circuit of one of said frequency transformers, means whereby a signaling current 75 so the frequency of which is a multiple of said fundamental frequency flows in said output circuits, there being also produced objectionable side-frequencies which flow in said circuits, circuit arrangements associated with 80 said transformer output circuits, each comprising a plurality of acceptor circuits, one for each of a pair of said objectionable side frequencies whereby such objectionable frequencies are by-passed from portions of the 85 circuit carrying the active signaling currents, said acceptor circuits for said side frequencies being so tuned that in their combined action they constitute rejector circuits for the respective active signaling frequencies in 90 said transformer output circuits. 95

55 3. In a wireless signaling system, a plurality of iron-cored frequency transformers arranged in cascade connection, each having an input and output circuit, means for applying a fundamental frequency to the input circuit of one of said frequency transformers, a signaling circuit, means whereby signaling 100 and other objectionable frequencies of said fundamental frequency flow in the output 105 circuits of said frequency transformers and a circuit arrangement associated with the output circuit of said first frequency transformer comprising acceptor circuit for each of said objectionable frequencies, whereby 110 said frequencies are by-passed from portions of the circuit that are in operative relation with a following active signaling circuit, the tuning conditions of said acceptor circuits being so adjusted that in their combined 115 action they constitute a rejector circuit for the multiplied frequency in the output circuit of said first frequency transformer.

60 4. In a signaling system, a high frequency generator in which a plurality of objectionable side frequencies occur besides a definite signaling frequency, a signaling circuit connected to said generator, means for suppressing said side frequencies from said signaling circuit comprising a plurality of acceptor circuits, one for each of said side frequencies, arranged in by-pass relationship in respect to said signaling circuit, the tuning 120 conditions of said acceptor circuits being so 125 adjusted that in their combined action they 130

constitute a rejector circuit for the signaling frequency and a transmitting system connected to said signaling circuit for transmitting said signaling frequencies.

5. In combination with a high frequency generator in which besides the signaling frequency disturbing side frequencies symmetrically to the signaling frequency are generated, a generator circuit, a transmitter circuit connected to said generator circuit for transmitting said signaling frequency, means for suppressing said side frequencies from said transmitter circuit comprising a pair of acceptor circuits tuned to a pair of symmetric side frequencies and arranged in by-pass relationship in respect to said transmitter circuit, the tuning conditions of said acceptor circuits being so adjusted that in their combined action they constitute a rejector circuit for the signaling frequency and a transmitter circuit connected to said generator circuit for transmitting said frequencies.

In testimony whereof we have affixed our signatures.
